(57) **CLAIM**

The ornamental design for the set of parallel bars, as shown and described.

DESCRIPTION

FIG. 1 is a front, left, and top perspective view of the set of parallel bars showing my new design;

FIG. 2 is a rear, right, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of portion 9 shown in FIG. 2;

FIG. 10 is a second front, left, and top perspective view of the set of parallel bars, shown in an alternate configuration with the connecting members and fasteners removed for clarity of disclosure; and,

FIG. 11 is a third front, left, and top perspective view of the set of parallel bars, shown in an alternate configuration with the connecting members and fasteners shown disassembled for clarity of disclosure.

The dash-dash broken lines in the drawings depict portions of the set of parallel bars that form no part of the claimed design. The dot-dash broken lines represent boundaries of the enlarged portion shown in FIGS. 2 and 9 that form no part of the claimed design.
